UNITED STATES PATENT OFFICE.

NELSON BLOUNT, OF NEW YORK, N. Y., ASSIGNOR TO UNITED LAMP AND BURNER COMPANY, OF NEW YORK, N. Y., A CORPORATION OF DELAWARE.

DESIGN FOR A LAMP.

41,004.

Specification for Design.

Patented Nov. 29, 1910.

Application filed September 13, 1910. Serial No. 581,909. Term of patent 14 years.

To all whom it may concern:

Be it known that I, NELSON BLOUNT, a citizen of the United States, residing in the borough of Manhattan, in the city, county, and State of New York, have invented a new and original and ornamental Design for Lamps, of which the following is a specification, reference being had to the accompanying drawing, forming a part thereof.

The figure is a perspective view of the lamp, showing my new design.

I claim—

The ornamental design for a lamp, as shown.

NELSON BLOUNT.
